[57] CLAIM

The ornamental design for an offset neck container, as shown and described.

DESCRIPTION

FIG. 1 is a perspective view of the offset-neck container;

FIG. 2 is a top plan view showing my new design thereof;

FIG. 3 is an end elevational view as seen from the left of FIG. 1;

FIG. 4 is a side elevational view, the opposite side is a mirror image thereof except for the conventional screw threading on the bottle of the neck;

FIG. 5 is an end elevational view as seen from the right of FIG. 1; and,

FIG. 6 is a bottom plan view thereof.
